[57] ABSTRACT

A rotary machine apex seal having an air directing passage connected by communicating passages in the rotor and housing to an external air pressure supply for directing air pressure to impinge upon the machine's internal peripheral wall to provide a cushion of air between the apex seal and this wall.

5 Claims, 6 Drawing Figures

ROTARY MACHINE APEX SEAL

This invention relates to a rotary machine apex seal and more particularly to a rotary machine apex seal running against a rotor housing on an air cushion.

In rotary machines such as rotary combustion engines, pumps, compressors and the like, wherein a seal arrangement is provided at each rotor apex to continuously sealingly engage an internal peripheral wall to separate the machine's working chambers which rotate with the rotor, one of the major considerations is minimization of the wear of the apex seals. There are two primary approaches to this objective, one being the choice of peripheral wall and seal materials for compatibility and wear life and the other being in the area of apex seal design. Up to the present time the choice of materials has been substantially limited by the sliding friction encountered in conventional seal designs.

The rotary machine apex seal according to the present invention provides for a wider than normal choice of materials by having a surface with a substantial area that is opposite and remains adjacent to the rotor housing's internal peripheral wall without radial movement as the rotor rotates. An air directing passage extends through this seal surface and is connected by a passage in the rotor and a communicating passage in the housing to an external air pressure supply. Air pressure is directed by the passage in the seal to impinge upon the internal peripheral wall to provide a cushion of air between the seal and this wall so that the seal runs on an air cushion rather than having sliding contact with the wall.

An object of the present invention is to provide a new and improved rotary machine apex seal.

Another object is to provide in a rotary machine an apex seal that runs against the rotor housing on a cushion of air derived from an external air pressure supply.

Another object is to provide in a rotary machine a rotor apex seal that has a passage connected to deliver air from an external air pressure supply via communicating rotor and housing passages to impinge upon the rotor's internal peripheral wall to provide a cushion of air between the seal and the internal peripheral wall as the rotor rotates.

Another object is to provide an apex seal for a rotary machine wherein an external air pressure supply is utilized to effect an air cushion between each apex seal and the rotor housing's internal peripheral wall to minimize seal wear.

These and other objects of the present invention will become more apparent from the following description and accompanying drawing in which:

FIG. 1 is a longitudinal sectional view of a rotary machine having one embodiment of the apex seals according to the present invention.

FIG. 2 is a reduced view taken along the line 2—2 in FIG. 1.

FIG. 3 is a view taken along the line 3—3 in FIG. 1.

FIG. 4 is an enlarged view of one of the apex seals taken along the line 4—4 in FIG. 1.

FIG. 5 is a view similar to FIG. 2 of a rotary machine having another embodiment of the apex seals according to the present invention.

FIG. 6 is a view similar to FIG. 3 for the apex seals in FIG. 5.

The apex seal according to the present invention is for use in rotary machines including rotary combustion engines, compressors, pumps and the like. Referring to

FIGS. 1 and 2, the rotary machine may, for example, be an internal combustion engine of the Wankel type comprising a stationary outer body or housing 10 having a rotor cavity 12 that is defined by an inwardly facing internal peripheral wall 14 of a rotor housing 15 and a pair of inwardly facing end walls 16 of end housing 17. In the Wankel engine the peripheral wall 14 is in the shape of a two-lobed epitrochoid or a curve parallel thereto and a rotor 18 having the general shape of a triangle with three peripheral faces 20 is mounted within the rotor cavity 12 on an eccentric 22 of a crankshaft 23. Crankshaft 23 is rotatably mounted outboard of the rotor cavity in sleeve bearings 24 fixed in the end housings 17 for rotation about the center line 25 of peripheral wall 14. An annular external toothed gear 26 is integral with the inboard end of the right-hand sleeve bearing 24 as viewed in FIG. 1 and is thus affixed to the housing 10 and meshes with an internal toothed ring gear 27 which is concentric with and secured to the rotor 18. The meshing gears 26 and 27 enforce a fixed, cyclic relation between the rotor and the crankshaft while the rotor faces 20 cooperate with the peripheral wall 14 and end walls 16 to define three variable volume combustion or working chambers 28. The chambers 28 are peripherally spaced around the rotor and move with the rotor within the housing as the rotor rotates about its axis 29 and planetates with respect to the crankshaft axis 25 to rotate crankshaft 23. As shown in FIG. 2, a fuel-air inlet passage 30 whose opening and closing is effected by motion of the rotor 18 provides for periodic admission of fuel-air mixture to each chamber 28, a spark plug 31 provides for ignition of the fuel-air mixture after compression and an exhaust passage 32 whose opening and closing is also effected by the motion of the rotor 18 provides for exhaust of the products of combustion from each chamber as the rotor rotates in the direction indicated by the arrow with each chamber undergoing intake, compression, expansion and exhaust to provide a power phase for each revolution of the crankshaft 23. The structure thus far described is conventional and operates efficiently assuming there is effective sealing between the working chambers of the engine.

Sealing of the chambers 28 is effected by a sealing arrangement comprising an apex seal 33 at each rotor apex and side seals 36 on each rotor side which extend between adjacent apex seals with an intermediate corner seal 37 near each rotor apex providing a sealing link between adjacent side and apex seals. Referring to FIGS. 1, 2 and 3, each of the apex seals 33 is mounted in an axially extending, radially outwardly facing groove 38 at each rotor apex that extends axially from one rotor side to the other with the apex seal being received at its outboard ends in an axially extending, radially outwardly facing groove 39 in the corner seals 37. The side seals 36 are mounted in accommodating arcuate grooves in the two sides of the rotor and extend between and sealingly engage the corner seals 37 which are mounted in accommodating apertures 40 in the sides of the rotor contiguous with the opposite ends of each apex seal groove 38. Both the side seals 36 and corner seals 37 are urged by suitable springs, not shown, to engage the end walls 16. In addition to this gas sealing arrangement, there is provided in each rotor side a circular oil seal 41. The oil seals 41 are mounted radially inward of the side seals 36 in accommodating circular grooves in the two sides of the rotor 18, these

oil seal grooves being concentric with the rotor axis 29. The oil seals 41 are urged by suitable springs, not shown, to engage the rotor cavity's end walls 16.

Referring to FIGS. 1 and 4, each of the apex seals 33 according to the present invention has a radially inwardly facing rectangularly shaped groove 42 that extends axially from near one end of the seal to near the other end. The base of the apex seal groove 38 is provided with a central rectangularly shaped raised portion that extends radially outward into the apex seal groove 42 a distance exceeding the maximum distance the apex seal can move radially in groove 38 with respect to the rotor. The walls of the apex seal groove 42 and the raised base portion of the rotor seal groove 38 cooperatively define an air chamber 43. Longitudinally extending, circumferentially spaced slots 44 in seal 33 are connected to the chamber 43 and extend radially out through the radially outwardly facing apex seal surface 46. The seal surface 46 is curved in cross-section as shown in FIGS. 2 and 4 to remain close over a substantial area to the internal peripheral wall 14 without requiring radial seal movement as the rotor planetates. Furthermore, this apex seal surface area that remains close to the internal peripheral wall 14 is made substantially larger than the radially inwardly facing pressure responsive area of the apex seal exposed to chamber 43 so that when air pressure is supplied to chamber 43, the lower air pressure acting on the apex seal surface 46 that results from the pressure drop across passages 44 provides a force that will counteract the radially outwardly directed force provided by the larger pressure in chamber 43 acting on the smaller radially outwardly facing force producing area of the apex seal to provide for the apex seal surface 46 riding on a cushion of air rather than having sliding contact with the internal peripheral surface 14. Air pressure is supplied to the apex seal chambers 43 from an air pressure supply 48 that may be provided by suitable means such as a turbine compressor driven by engine exhaust gases or a pump driven by the engine crankshaft.

Referring to FIGS. 1 and 3, connection of the air pressure supply 48 to the chamber 43 of the apex seals 33 is provided by an axially facing circular port 50 that is formed in one of the end walls 16 concentric with the crankshaft axis 25 and is connected by an axially extending passage 52 through the associated end housing 17 to an air pressure supply line 54 from the air pressure supply 48 so that the air pressure is thus always made available to this port. An axially leftward facing circular port 55 is formed in the opposing side of rotor 18 between the oil seal 41 and the side seals 36 and concentric with the rotor axis 29. The rotor port 55 is radially disposed as shown in FIGS. 1 and 2 so that during planetation of the rotor 18 it always remains open to the housing port 50. The rotor port 55 is connected to the apex seal chambers 43 by three equally angularly spaced, radially extending passages 58 in the rotor 18 through the raised base portion of the apex seal grooves 38. During engine operation and with supply of the air pressure to the air passages 44 in the apex seals 33 via the communicating air pressure ports 50 and 55 and the passages 58, air pressure is directed by the passages 44 to impinge upon the peripheral wall 14. The differential pressure acting on the differential pressure responsive area of each apex seal 33 acts to separate each apex seal from the rotor housing by a small distance such as several microns and effect a cushion or blanket

of air between the apex seal and the internal peripheral walls and an air barrier between adjacent chambers as the rotor rotates instead of sliding contact.

In the FIG. 1 - 4 embodiment there is thus a single air pressure supply to float the apex seals and as a result this pressure must be high enough to ensure air flow out through the apex seals against the highest gas pressure experienced in the working chambers during each rotor revolution. In the particular rotary machine the gas pressure resisting air flow out through the apex seals may be divided into three distinct levels with the lowest occurring during that third of a rotor revolution where an apex seal passes from exhaust to intake, the next higher level occurring during the next third of a rotor revolution where this apex experiences the compression phase and the highest level during the last third of a rotor revolution where this apex seal experiences the expansion phase. To allow the use of lower pressures which are sufficient during certain portions of the cycle to maintain the air flow and thereby reduce air pressure supply requirements, there may be provided several air pressure supplies of different pressures tailored to the particular application as shown by the embodiment in FIGS. 5 and 6, wherein portions similar to those shown in FIGS. 1 - 4 are identified by the same numerals only primed and new parts are identified by new numerals. Referring to the FIGS. 5 - 6 embodiment, there is provided an air pressure supply system having three separate air pressure supplies 62, 64 and 66 having low, intermediate and high pressures which are connected as schematically shown to three radially extending ports 68, 70 and 72, respectively, in one end wall 16'. The ports 68, 70 and 72 are equally spaced 180° apart about axis 25' with the low pressure port 68 intermediate the inlet port 30' and the exhaust port 32' and the intermediate and high pressure ports 70 and 72 located in that order from the low pressure port 68 in the clockwise direction. The ports 68, 70 and 72 are periodically opened during each rotor revolution to three equally angularly spaced arcuate ports 74, 76 and 78 in the opposing rotor side which are separately connected by the radially extending delivery passages 58' to the chambers 43' of the apex seals 33'. The arcuate air ports 74, 76 and 78 in the rotor each extend almost 120° and thus are periodically connected during substantially one-third of each rotor revolution to the housing air ports 68, 70 and 72, respectively, as the rotor planetates. With this arrangement of porting and connection of the particular air pressure supplies, low pressure is periodically delivered via housing port 68 to each of the arcuate rotor ports 74, 76 and 78 to effect air flow against the lowest gas pressures to float the respective apex seals 33 as they traverse the low engine pressure region during the latter portion of the exhaust phase and the beginning portion of the intake phase. Similarly, intermediate pressure is periodically delivered via housing port 70 to each of the arcuate rotor ports 74, 76 and 78 to effect air flow against higher gas pressures to float the respective apex seals 33 as they traverse an intermediate engine pressure region during the latter portion of the compression phase and the beginning of the expansion or power phase. Then during the remaining portion of the expansion phase and the beginning of the exhaust phase, high pressure is periodically delivered via housing port 72 to each of the arcuate ports 74, 76 and 78 to effect air flow against the highest gas pressures to float the respective apex seals 33 as they

traverse the high engine pressure region during this portion of the engine cycle. Thus, as each apex seal passes through a complete cycle it is floated by supply of low, intermediate and high pressures according to the pressures encountered in the cycle whereby there is effected floating of the seals with a reduction in total air pressure supply.

The above described embodiments are illustrative of the invention which may be modified within the scope of the appended claims.

I claim:

1. In a rotary machine a housing having an internal peripheral wall and opposite internal end walls cooperatively defining a rotor cavity, a crankshaft rotatably mounted in said housing, a rotor in said rotor cavity eccentrically rotatably mounted on said crankshaft, said rotor having a plurality of apexes that remain adjacent said internal peripheral wall when said rotor and said crankshaft rotate, said rotor further having peripheral faces extending between said apexes that cooperate with said cavity walls to define a plurality of chambers that vary in volume and move with said rotor as said rotor and said crankshaft rotate, apex seal means mounted on each said apex of said rotor for continuously providing sealing between said internal peripheral wall and said rotor to sealingly separate adjacent chambers as said rotor and said crankshaft rotate, each said apex seal means comprising an elongated apex seal member mounted in an axially extending radially outwardly facing groove in the respective apex portion of said rotor for radial movement outward toward and inward from said internal peripheral wall, each said apex seal member having a radially outwardly facing surface with a substantial area that is opposite and remains adjacent to said internal peripheral wall without radial seal member movement when said rotor and said crankshaft rotate, external air pressure supply means, and air passage means in each said apex seal member extending through said surface and operatively connected to said external air pressure supply means for directing air pressure to impinge upon said internal peripheral wall to provide an air pressure force which acts to separate each said apex seal member and said internal peripheral wall to effect a cushion of air therebetween when said rotor and said crankshaft rotate.

2. In a rotary machine, a housing having an internal peripheral wall and opposite internal end walls cooperatively defining a rotor cavity, a crankshaft rotatably mounted in said housing, a rotor in said rotor cavity eccentrically rotatably mounted on said crankshaft, said rotor having a plurality of apexes that remain adjacent said internal peripheral wall when said rotor and said crankshaft rotate, said rotor further having peripheral faces extending between said apexes that cooperate with said cavity walls to define a plurality of chambers that vary in volume and move with said rotor as said rotor and said crankshaft rotate, apex seal means mounted on each said apex of said rotor for continuously providing sealing between said internal peripheral wall and said rotor to sealingly separate adjacent chambers as said rotor and said crankshaft rotate, each said apex seal means comprising an elongated apex seal member mounted in an axially extending radially outwardly facing groove in the respective apex portion of said rotor for radial movement outward toward and inward from said internal peripheral wall, each said apex seal member having a radially outwardly facing surface

with a substantial area that is opposite and remains adjacent to said internal peripheral wall without radial seal member movement when said rotor and said crankshaft rotate, each said apex seal member further having a surface including a radially inwardly facing surface portion smaller than said radially outwardly facing surface co-operating with said rotor to provide an air chamber, external air pressure supply means, air passage means in said rotor operatively connecting said external air pressure supply means and each of said air chambers, and air passage means in each said apex seal member extending through said outwardly facing surface and connected to the respective air chamber for directing air pressure to impinge upon said internal peripheral wall to provide an air pressure force which acts to separate each said apex seal member and said internal peripheral wall and effect a cushion of air therebetween when said rotor and said crankshaft rotate.

3. In a rotary machine, a housing having an internal peripheral wall and opposite internal end walls cooperatively defining a rotor cavity, a crankshaft rotatably mounted in said housing, a rotor in said rotor cavity eccentrically rotatably mounted on said crankshaft, said rotor having a plurality of apexes that remain adjacent said internal peripheral wall when said rotor and said crankshaft rotate, said rotor further having peripheral faces extending between adjacent apexes that cooperate with said cavity walls to define a plurality of chambers that vary in volume and move with said rotor as said rotor and said crankshaft rotate, apex seal means mounted on each said apex of said rotor for continuously providing sealing between said internal peripheral wall and said rotor to sealingly separate adjacent chambers as said rotor and said crankshaft rotate, each said apex seal means comprising an elongated apex seal member mounted in an axially extending radially outwardly facing groove in the respective apex portion of said rotor for radial movement outward toward and inward from said internal peripheral wall, each said apex seal member having a radially outwardly facing surface with a substantial area that is opposite and remains adjacent to said internal peripheral wall without radial seal member movement when said rotor and said crankshaft rotate, external air pressure supply means, air passage means in said housing extending through one of said end walls and connected to said external air pressure supply means, air passage means in said rotor operatively connected to said housing air passage means at said one end wall, and air passage means in each said apex seal member extending through said surface along substantially the length thereof and operatively connected to said rotor air passage means for directing air pressure to impinge upon said internal peripheral wall to provide an air pressure force which acts to separate each said apex seal member and said internal peripheral wall and effect a cushion of air therebetween when said rotor and said crankshaft rotate.

4. In a rotary machine, a housing having an internal peripheral wall and opposite internal end walls cooperatively defining a rotor cavity, a crankshaft rotatably mounted in said housing, a rotor in said rotor cavity eccentrically rotatably mounted on said crankshaft, said rotor having a plurality of apexes that remain adjacent said internal peripheral wall when said rotor and said crankshaft rotate, said rotor further having peripheral faces extending between said apexes that cooperate with said cavity walls to define a plurality of chambers

that vary in volume and move with said rotor as said rotor and said crankshaft rotate, apex seal means mounted on each said apex portion of said rotor for continuously providing sealing between said internal peripheral wall and said rotor to sealingly separate adjacent chambers as said rotor and said crankshaft rotate, each said apex seal means comprising an elongated apex seal member mounted in an axially extending radially outwardly facing groove in the respective apex portion of said rotor for radial movement outward toward and inward from said internal peripheral wall, said apex seal member having a radially outwardly facing surface with a substantial area that is opposite and remains adjacent to said internal peripheral wall without radial seal member movement when said rotor and said crankshaft rotate, each said apex seal member further having a surface including a radially inwardly facing surface portion smaller than said radially outwardly facing surface cooperating with said rotor to provide an air chamber, a plurality of external air pressure supply means having different air pressures, air passage means in said rotor operatively sequentially connecting said plurality of air pressure supply means to said air chambers, and air passage means in each said apex seal member extending through said outwardly facing surface and connected to the respective air chamber for directing the different air pressures supplied thereto to impinge upon said internal peripheral wall to provide an air pressure force which acts to separate each said apex seal member and said internal peripheral wall and effect a cushion of air therebetween when said rotor and said crankshaft rotate.

5. In a rotary machine, a housing having an internal peripheral wall and opposite internal end walls cooperatively defining a rotor cavity, a crankshaft rotatably mounted in said housing, a rotor in said rotor cavity eccentrically rotatably mounted on said crankshaft, said

rotor having a plurality of apexes that remain adjacent said internal peripheral wall when said rotor and said crankshaft rotate, said rotor further having peripheral faces extending between adjacent apexes that cooperate with said cavity walls to define a plurality of chambers that vary in volume and move with said rotor as said rotor and said crankshaft rotate, apex seal means mounted on each said apex portion of said rotor for continuously providing sealing between said internal peripheral wall and said rotor to sealingly separate adjacent chambers as said rotor and said crankshaft rotate, each said apex seal means comprising an elongated apex seal member mounted in an axially extending radially outwardly facing groove in the respective apex portion of said rotor for radial movement outward toward and inward from said internal peripheral wall, each said apex seal member having a radially outwardly facing surface with a substantial area that is opposite and remains adjacent to said internal peripheral wall without radial seal member movement when said rotor and said crankshaft rotate, a plurality of external air pressure supply means having different air pressures, air passage means in said housing connected to each of said air pressure supply means, air passage means in said rotor for each said apex seal means operatively sequentially connected to said housing air passage means during each rotor revolution, and air passage means in each said seal member connected to only one of said rotor air passage means for directing the different air pressures supplied thereto to impinge upon said internal peripheral wall to provide an air pressure force which acts to separate each said apex seal member and said internal peripheral wall and effect a cushion of air therebetween when said rotor and said crankshaft rotate.
